UNITED STATES PATENT OFFICE.

WILLIAM GRAY, OF BROOKLINE, MASSACHUSETTS.

VEHICLE-LAMP.

1,235,564.

Specification of Letters Patent. Patented Aug. 7, 1917.

Application filed March 18, 1915. Serial No. 15,153.

To all whom it may concern:

Be it known that I, WILLIAM GRAY, a citizen of the United States, residing at Brookline, in the county of Norfolk and State of Massachusetts, have invented certain new and useful Improvements in Vehicle-Lamps; and I do hereby declare the following to be a full, clear, and exact description of the invention, such as will enable others skilled in the art to which it appertains to make and use the same.

The present invention relates to an improvement in vehicle lamps. In automobile lamps now in use, a parabolic reflector is used with an incandescent lamp bulb supported with its filament at or near the focus of the reflector. In use, these lamps project a beam of light from the lamp in the direction of the axis of the reflector, but some rays are emitted directly from the filament itself, and these rays, together with some reflected rays emanating from portions of the filament not located at the focus of the reflector are dispersed, and pedestrians and other persons using the road, meeting a vehicle carrying such lamps are often more or less blinded by the dazzling light. A great variety of attempts have been made to produce non-glaring or non-dazzling lamps which will efficiently light the road and at the same time not dazzle or impair the vision of persons meeting the vehicle carrying such lamps. The object of the present invention is to produce a head lamp of such construction that persons traveling along a road, either on foot or in vehicles, will not be blinded by the lamps of an approaching vehicle carrying lamps of the construction of this invention, while the driver of that vehicle will have good road illumination. To this end the present invention consists in the lamp hereinafter described and particularly defined in the claims.

In the accompanying drawings illustrating the preferred form of the invention, Figure 1 is a plan, Fig. 2 a front elevation; and Fig. 3 a side elevation of the lamp.

The body 1 of the lamp is of general para-

bolic form and carries the usual parabolic reflector and incandescent lamp in the usual manner. The front portion, however, of the lamp body is extended forward at 2 at the top and bottom, and the front glass is made of two portions, so that the lamp front is V-shaped in horizontal section. Viewing the lamp in front elevation, as seen in Fig. 2, the right-hand portion 3 is of frosted glass, being, therefore, non-transparent or impervious to direct light transmission, while the left-hand portion 4 is of clear glass, or transparent material. The clear glass portion comprises one vertical half of the lamp front and affords full road illumination, while the frosted portion 3 comprises the other vertical half of the lamp front and prevents rays of light extending from the lamp toward the left, so that persons on foot or in vehicles on the left-hand side of the vehicle will not be dazzled by light from the lamp. In America, where the rule of the road requires one to pass vehicles moving in the opposite direction by turning to the right, the frosted portion of the glass would be in the position shown in the drawings, that is, on the right-hand side of the lamp, as viewed from the front, while elsewhere, in places where the rule of the road requires meeting vehicles to pass to the left, the frosted portion would be on the left-hand side of the lamp, as viewed from the front. This can conveniently be accomplished by turning it upside down.

This lamp may have a body of any desired form. It is requisite, however, that the front glass should lie far enough in front of the filament so that direct rays therefrom can not be seen on the blind or left-hand side of the medial line of the left-hand lamp of the vehicle. It is not essential that the light-impervious side of the lamp wholly cut off all light from that side so long as it cuts off the direct transmission of light. So, the word impervious, as used herein, is not intended to limit the invention to constructions in which illumination is afforded by the blind side of the lamp.

Having thus described the invention, what is claimed is:—

1. A vehicle lamp having a body and front closure, V-shaped in horizontal cross-section, one side of which is of non-transparent material and the other side of which is of transparent material.
2. A vehicle lamp having a body and front

closure, V-shaped in horizontal cross-section, one side of which is of non-transparent material.

WILLIAM GRAY.
